ADJUSTABLE FEEDER FOR PENS

Ross F. George, Seattle, Wash.

Application March 8, 1937, Serial No. 129,531

17 Claims. (Cl. 120—114)

The present invention relates to artists' pens, such as are used for freehand drawing or lettering, and is particularly intended to provide a means whereby the capillary channels, whether between the adjacent nibs or between the pen tip and an underfeeder or an overfeeder, or two such feeders, can be varied in width or thickness, thereby to accommodate the pen, and the feeder or feeders if employed, to inks or colors of greater body or of lesser body.

Heavy inks or colors (hereinafter referred to as inks) will not feed properly along narrow capillary channels and the depth or width of these channels must be sufficient to afford proper feed when such heavy inks are to be used. On the other hand, thinner inks, those having less body, will tend to run too freely and to blot or smear if the capillary channels are of too great capacity (width or depth). In order, therefore, that a given pen may be usable at will for lighter bodied inks or for heavier bodied inks it is necessary that the capillary channels be variable or adjustable in capacity, and it is to this end that the present invention is directed.

The principles of my invention may be illustrated in conjunction with a pen without any feeder, the adjustment being made in the spacing of the nibs, or the invention may be embodied in the combination of a pen and a feeder, which may be either an underfeeder or an overfeeder, or indeed in conjunction with two such feeders, and the adjustment may involve varying, usually simultaneously and by a single means, the spacing between the tip of one or both feeders and the pen tip, and if desired, the spacing between the nibs as well.

It is a further object of the invention to provide adjusting means of the character indicated which may be readily manufactured and assembled, and which will be convenient in use.

It is also an object to provide such an adjusting means which may be adjusted into one of two or more definite positions, and which may be maintained readily in any one of such positions, or alternatively, an adjusting means which may accomplish several degrees of adjustment, depending upon the particular position in which the adjusting means is placed.

The style of the pen is relatively unimportant, and may vary widely, as shown in the drawings, as may also the style and mounting of the feeder or feeders. My invention, however, is shown in conjunction with feeders of the general type illustrated in my copending application Serial No. 81,822, filed May 26, 1936.

My invention, having in mind the above objects and others as will appear hereinafter, comprises the novel parts and the novel combination and arrangement thereof, as shown in the accompanying drawings, described in this specification, and as will appear more particularly in the claims at the end of this specification.

In the accompanying drawings my invention has been shown in various illustrative forms.

Figure 1 is a longitudinal section through a pen and feeder, of the type shown in my copending application referred to above, illustrating a simple form of adjustment between a single feeder and the pen. Figure 2 is a similar view illustrating an adjustment between two such feeders and a pen. Figure 3 is a similar view showing the adjustment between a different type of feeder and a pen.

Figure 4 is an elevation, and in part a section on the line 4—4 of Figure 5, illustrating a different type of adjusting means, and Figure 5 is a longitudinal section on the line 5—5 of Figure 4.

Figure 6 is an elevation of a pen, showing a means for adjusting the spacing between the usual two nibs of a pen. Figure 7 is a similar elevation, showing an arrangement which will secure several degrees of adjustment, and Figure 8 is a view similar to Figure 7, showing the same idea applied to a pen with three nibs. Figure 9 is an enlarged detail section on the line 9—9 of Figure 7.

Figure 10 is an elevation, with parts broken away, Figure 11 is a longitudinal section, illustrating an adjustment of feeders relative to a pen, and Figure 12 is a view similar to Figure 10, showing parts in a differently adjusted position, and illustrating the possibility of adjustment of the pen nibs simultaneously with adjustment of the two feeders.

Figure 13 is a longitudinal section through a pen and feeder, showing the adjusting means mounted on the feeder for disposal in two definite positions.

Figure 14 is a longitudinal section through a pen and two feeders, showing the adjusting means operative only upon the two feeders, and not necessarily upon the pen.

Figure 15 is an elevation and Figure 16 a longitudinal section of a pen and feeder, wherein adjustment of the spacing of the tips is accomplished by movement of the feeder longitudinally of the pen, and Figures 17 and 18 are longitudinal sections of pen and feeder combinations similarly adjustable. Figure 18A is a cross section of the arrangement of Figure 18.

Figure 19 is an elevation of a pen and feeder combination, similar to Figures 15 to 18, but wherein longitudinal adjustment is accomplished only between certain definite positions, and is 5 accompanied by a relative lateral movement.

The pen 1, as I have indicated above, may be of any type suitable for artist's work, such as drawing or lettering. It is longitudinally slit at its tip to provide two or more nibs, such a slit 10 being indicated at 10, and this slit, in addition to giving flexibility to the pen, serves as a capillary channel along which the ink flows to the writing tip, indicated at 11.

As in my copending application, referred to 15 above, the shank of the pen may be apertured and struck up to form pivot ears 12, and a feeder such as the overfeeder 2 is pivotally mounted between these ears upon a pivot axis indicated at 20 21. The feeder may have a rearwardly extending foot 20, engageable with a tongue 13, formed preferably as part of the pen body and projecting into the aperture from which the ears 12 are struck up. The tongue 13 thereby constitutes a spring, bearing upon the foot 20 of the feeder to press 25 its tip 23 towards the tip 11 of the pen. Alternatively, or in conjunction with such a spring-tongue, the ears 12 may press inwardly upon inclined rear edges of the feeder, to press its tip 30 towards the pen tip, as disclosed in my copending application. The pivoting of the feeder permits it to be thrown back from the pen for cleaning, yet in operative position as shown, its tip is always pressed towards the pen tip.

While a true pivot mounting is shown in this 35 form, and in others, it is accompanied by means, such as the tongue 13, to produce pressure of the feeder tip towards the pen tip. The same result can be obtained by securing the feeder at 24 to the pen, at a point distant from the tip, and 40 supporting it by means of a flexible neck, as is illustrated in Figure 4, for example. Either such arrangement is in effect a hinge mounting, and either is a flexible or spring-pressed mounting, at least, for the purposes of the present invention, 45 hence these terms are herein intended to be synonymous.

As shown in the arrangement of Figure 2, an underfeeder 3 may be hingedly mounted at 31 in the shank of the pen, and in such a manner as 50 to press its tip 33 towards the tip 11 of the pen, and in these respects the pen and feeders are or may be constructed similarly to any one of the arrangements disclosed in my copending application.

In the arrangement shown in Figure 1 a screw 4 is threaded in the feeder 2, and its end bears upon the pen 1, reacting in opposition to the spring mounting. By screwing the screw 4 in or out the spacing between the tips 23 and 11 of the 55 feeder and pen, respectively, can be varied, and thus this capillary channel can be increased or decreased in capacity to accommodate inks of different body.

In the arrangement shown in Figure 2 the tips 60 of both feeders are spring-pressed toward the pen tip, and the screw 4 passes through a slot or aperture 14 in the pen, being shown as reduced in diameter to form the extension 40 which bears on the underfeeder 3 to press the latter away from the pen simultaneously with the pressure 65 of the overfeeder away from the pen.

In the arrangement shown in Figure 3 the underfeeder 3, hinged at 31, has an extension or foot 32 which engages the spring tongue 13, 70 and the latter, adjacent the foot 32, is provided

with two transverse grooves 15, whereby, by engagement of the end of the foot 32 in one or the other of the grooves 15, to space the tip 33 of the underfeeder a greater or lesser distance away from the tip 11 of the pen.

In Figures 4 and 5 the overfeeder 2 is slotted to provide pivot ears 25, and a cam or disk 41 is eccentrically pivoted between these ears at 42, and bears upon the pen to space the tip 23 of the feeder a greater or lesser distance from the tip 10 15 11 of the pen. The periphery of the disk 41 may be knurled or otherwise roughened to prevent its slipping relative to the pen, although when ink has been applied to the surfaces the frictional grip is improved, and it is unlikely that they will 20 slip, even though the periphery of the disk be not roughened.

In Figure 6 a slot 15 is provided as an extension of the slit 10 which defines the nibs, and in this slot is received a pin 5. Preferably the slot is 25 of a width at its inner end, that is, the end distant from the tip 11, equal to or slightly greater than the thickness of the pin 5, and heads 50 and 51 prevent the pin from falling out. At its outer end, that is, the end nearest the tip, the slot 15 30 may be of equal width, or it may be reduced in width, and slight nubs 16 are formed at the entrance to this narrow portion so that the pin 5 can be pressed into this narrow portion and retained there by the nubs 16, thus definitely holding the pin in at least two definite positions. In the latter position, if the outer end of the slot is narrower than the pin, the nibs of the pen will be spread apart, thus increasing the capacity of the capillary channel defined by the slit 10, and 35 making it capable of accommodating inks of heavier body. In this form no feeder is shown in conjunction with the pen, although one or two feeders may be used if desired, and ordinarily a suitable feeder or feeders would be used, 40 the head 50 of the pin serving to space the feeder tip from the pen tip, more or less, in the two different positions described.

A similar arrangement is shown in Figure 7, where, however, the slot 15 may be progressively 45 decreased in width towards the tip, but in any event the pin 5 is held in any one of several positions lengthwise of the slot, thus to vary by several degrees the spacing of the tips, and, if the slot is progressively narrowed, the width of the 50 slit 10. A similar arrangement is shown in Figure 8, where, however, the pen has three nibs, and instead of a single pin there is a U-shaped member 5', the two legs of which are received in the respective slots 15.

In Figures 10, 11 and 12 both an overfeeder 2 and an underfeeder 3 are shown, and the respective heads 50 and 51 of the pin 5, sliding lengthwise of the slot 15, engage the feeders 2 and 3. In the form of Figure 12, at the same time that 60 the nibs are being spread apart the heads may space the feeder tips from the pen tip. Spacing of the feeder tips from the pen tip occurs because the feeder tips are inclined toward the pen tip, consequently sufficient movement of the heads of 65 the pin 5 from an inoperative position at a point most distant from the tip 11 towards operative position, in a direction towards the pen tip, brings them into contact with the inclined inner faces of the feeders, and acts to spread the feeders at 70 their tips away from the pen tip.

The slot 15, in Figures 10 and 11, has three enlargements at 18, to retain the pin 5 in three definite positions lengthwise of the slot, due, of course, to the resilient tendency of the pen to 75

resist spreading of the nibs. In that position most distant from the tip, the heads of the pin will not contact with the feeders, and, the enlargement being as large as the pin, the nibs are not spread apart. In the next position, as shown, the heads engage the feeders, and space their tips from the pen tip, but the enlargement may be as large as the pin, so that the nibs are still not spread apart. In the third position the feeders are still, or more widely spaced from the pen tip, and if the enlargement is of smaller size than the pin, the nibs will be spread apart also. If the last enlargement is equal in size to the pin, the nibs will not be spread. If the two positions first described provide sufficient adjustment the third may be omitted, or if more positions, and a finer adjustment, is desired, the number of enlargements may be increased.

The same general arrangement can be employed in the form illustrated in Figure 13, wherein the pin 5 is received in a slot 26 extending lengthwise of the feeder 2. This makes the adjustment of the pin 5 somewhat easier, and the feeder may be slightly deformed, as indicated by the bump 27 in Figure 13, to hold the pin 5 either in the inoperative position shown in the dot and dash lines or in an operative position shown in full lines.

Should it be desirable to use an underfeeder and an overfeeder both, the pin 5 may be supported in the slot 26 in the overfeeder 2, or in the underfeeder if preferred, and as shown in Figure 14, it has a reduced portion 52 extending through the slot 15 in the pen to engage the pivotally mounted underfeeder. The width of the slot may vary as described in connection with Figures 10, 11 and 12, or it may not, as preferred. The underfeeder may be provided with a depression or pocket, indicated at 35, for the reception and definite positioning of the end 52 of the pin 5, thus securing, if desired, a definite spacing of the feeder tips from each other and from the pen tip, and maintaining parts in this adjusted position against any tendency to slip, as they might, due to flexing of the pen (and feeders) in use.

Instead of accomplishing the adjustment of the spacing of the tips by movement of a member lengthwise of the pen or feeder, the feeder itself may move lengthwise of the pen, and relative to cooperating spacer members on one or both of the pen and feeder. Thus, in Figures 15 and 16, the mounting 28 may be received in a slot 17 in the pen shank, so that the feeder 2 can be moved, by means of an upturned flange 29, lengthwise of the pen 1. The slot 17 may have cooperating enlargements similar to the enlargements 18, or equivalent means, to retain the feeder in any one of several definite positions. The feeder, near its tip, has a transverse channel or recess 6, to receive within it, in one position of the feeder, a transverse ridge or upraised bump 19 adjacent the pen tip. The feeder tip now lies close to the pen tip. In another position of the feeder, as shown in dotted lines, the inclined side of the channel 6 rides upon the ridge 19, spacing the feeder tip from the pen tip. In Figure 17 the same action occurs, the pivot mounting 21 sliding lengthwise in a slot in the pivot ears 12. In Figure 18, to accomplish the same result, the feeder is merely retained beneath opposite lips 24', struck up from the pen shank, and may be slid lengthwise of the pen and relative to these lips 24'.

In the form shown in Figure 19 the pin 7 which passes through the feeder and pen permits lateral swinging of the feeder. If the pin 7 is flattened

at one or more sides, and is received in an enlargement 70 at one end of a narrower slot 71 in the pen shank, the feeder 2 can not be moved lengthwise of the pen until it has been swung outwardly, as shown, rotating the pin 7 until a flattened side 5 is parallel to the edges of the slot 71. The pin's width in this position being no greater than the slot 71, it can be moved lengthwise of the slot, and upon its reaching the enlargement 72 the pin can be rotated, by swinging the feeder back 10 into alignment with the pen. The pin can not, in this new position, slide lengthwise of the slot, and the feeder is held in a definite position. In this latter position, as in the dotted line positions of Figures 16 and 17, the recess 6 cooperates with a 15 bump on the pen to space the feeder tip farther from the pen tip. Such an arrangement, in addition, facilitates cleaning of the pen and feeder.

It is believed that the principles of my invention will be understood from the foregoing, and it will be understood that these principles may be embodied in various forms, and in various combinations. Because of the small size of some of the parts it has been necessary in the drawings to exaggerate sizes and spacings, and it will be understood that the parts will be made of such size, and the spacings will be so regulated and adjusted, as to serve the respective purposes intended, as is well understood in this art, and it is 30 not necessary to make the parts or the spacings as great as is shown in the drawings, but they are necessarily so shown in exaggerated fashion for purposes of illustration.

The movement of feeder tips relative to the pen tip, and of the nibs relative to each other, has the advantage that it tends to loosen and break up any incrustation of dried ink at these points, and thereby makes the ink flow more freely, and lessens the likelihood of flakes of dry ink blurring 40 a line, or marring the smoothness of the line being drawn.

What I claim as my invention is:

1. In combination with an artist's pen, a feeder disposed with its tip in adjacent relationship 45 to the pen's tip to provide a capillary channel for the ink, and means to vary the spacing of said tips and substantially to maintain such spacing, to accommodate such channel to inks of different body.

2. In combination with a flexible pen, a feeder flexibly mounted on the shank of the pen, with its tip adjacent the pen tip, and means to vary the spacing of said tips, and substantially to maintain such spacing.

3. In combination with a pen, a feeder flexibly mounted on the shank thereof, with its tip adjacent the pen nibs, and means carried by the pen to hold the feeder tip spaced to definite distance from the pen nibs, regardless of flexing 60 of the pen, and to adjust such spacing.

4. In combination with a pen, a feeder flexibly mounted on the shank thereof, with its tip adjacent the pen nibs, and means supported from the feeder to adjust the spacing of the feeder 65 tip from the pen nibs.

5. In combination with a pen, a feeder swingably mounted on the shank thereof, with its tip adjacent the pen tip, and spacer means movable lengthwise of the pen and feeder, and reacting therebetween, to space the feeder tip apart from the pen tip, by definite distances which are dependent upon the position of adjustment of said spacer means.

6. In combination with a pen, a feeder flexibly 75

mounted on the pen, and guided thereon for movement lengthwise of the pen, and means co-operating between the pen and feeder to vary the spacing between their tips in accordance with the position of the feeder lengthwise of the pen.

7. In combination with a pen, a feeder flexibly mounted on the shank thereof, with its tip adjacent the pen nibs, and inclined away from the pen towards the mounting, as viewed in longitudinal section, and a button head disposed in the space between the feeder and pen, and guided for movement lengthwise of the pen and feeder, from an inoperative position wherein, of the pen and feeder, it is out of contact with one, and an operative position wherein it is in contact with both, to spread apart the tip and nibs.

8. The combination defined in claim 7, wherein in the pen is slotted lengthwise, and the button head is guided in such slot.

9. The combination defined in claim 7, wherein in the feeder is slotted lengthwise, and the button head is guided in such slot.

10. The combination of claim 2, and a second feeder flexibly mounted on the pen, the spacing-adjusting means being further engageable with the second feeder, to vary the spacing of its tip from the pen tip.

11. The combination of claim 7, and a second feeder mounted upon the pen at the side opposite the first feeder, and means carried by said button head and engageable with the second feeder, but only in the operative position of the parts, to space its tip from the pen nibs.

12. In combination with a pen constituting one member, and a feeder, constituting another member, flexibly mounted on the shank thereof, to dispose its tip adjacent the pen tip, and inclined towards the pen tip, one of said members being longitudinally slotted, a headed pin guided in said slot for movement lengthwise of the pen, its head, when it is at one end of the slot, being out of contact with one such member, and when it is at the other end of the slot engaging the

latter member to spread the tips of the two members apart, and means to positively maintain the pin and its head at will in each of two or more positions lengthwise of the slot.

13. The combination defined in claim 12, 5 wherein the slot is formed in the pen, in continuation of the slit defining the nibs thereof, and such slot is provided with inwardly directed nubs constituting the means to maintain the pin in position.

14. In combination with a pen, a feeder hingedly mounted on the shank of the pen, with its tip disposed adjacent the pen tip, spring means reacting between the pen and feeder to press the feeder tip towards the pen tip, and means reacting between the feeder and pen to adjust the spacing of the two tips into a plurality of different positions, and substantially to maintain each such spacing in all positions of use of the pen.

15. In combination with a pen, a feeder flexibly mounted upon the pen, with its tip adjacent the nibs of the pen, a spacer eccentrically pivoted on one thereof, and bearing upon the other, to vary the space between the feeder and pen 25 nibs.

16. In combination with a pen, a feeder mounted thereon for relative movement, and cooperating inclined surfaces formed on the pen and feeder, and engageable by such relative movement to hold the feeder tip and the nibs of the pen spaced more or less apart, in accordance with the relative positions of such inclined surfaces.

17. In combination with a pen, a feeder supported and guided thereon for sliding movement lengthwise of the pen, the pen having a transverse bump adjacent its tip, and the feeder having a transversely inclined surface cooperating therewith, upon lengthwise movement of the 40 feeder, to increase the spacing between the feeder and the nibs of the pen.

ROSS F. GEORGE.
